LOCKING BOLT AND ACTUATING AND
ANCHOR RELEASING MEANS THERE-
FOR

David A. Ramler, Brookline, Mass.

Application July 18, 1950, Serial No. 174,501

7 Claims. (Cl. 70—151)

1

My present invention relates to door locks and particularly to a lock which has its bolt normally held against being retracted from its locking position by a bolt anchor releasable as an incident to bolt retraction by means other than the outside handle.

While security requirements vary considerably, there is a real demand for a simple and strong lock in which the bolt is normally anchored against retraction by means of the outside handle and which is otherwise adapted for normal usage. The principal objective of this invention is to provide a door lock that will meet such general requirements.

In accordance with my invention, I provide a lock consisting of a support for a bolt that is movable between an exposed locking position and a retracted unlocked position and a bolt anchor operative when the bolt is in locking position but rendered inoperative as an incident to the unlocking of the door from the outside as with a key or by turning the inside handle. The outside handle is independently connected to the bolt so that it can not be turned to retract the bolt until the bolt anchor has been rendered inoperative.

Such a lock is well adapted to meet various security requirements for the bolt anchor may not only be positioned inoperatively by electrically operated means but such means also may be used to hold the bolt retracted.

The connection between the outside handle and the bolt may also be employed to hold the bolt retracted and this feature is of advantage since, when controlled by a latch operated release, engageable with the strike plate, the door is automatically locked when shut.

In the accompanying drawings, I have shown an illustrative embodiment of my invention from which these and other of its novel features and advantages will be readily apparent.

In the drawings:

Fig. 1 is a fragmentary view of the outside of a door equipped with a lock in accordance with my invention.

Fig. 2 is a partly sectioned view showing the lock from the inside and the door closed.

Fig. 3 is an elevation of the lock with the inside handle and cover plate removed.

Fig. 4 is a like view but with the inside support wall removed.

Fig. 5 is a view, similar to Fig. 4, but partly sectioned to show the position of the parts when the bolt is in its locking position.

Fig. 6 is a view, similar to Fig. 5, but showing

2

the position of the parts when the bolt is retracted.

Figs. 7 and 8 are sections along the lines 7—7 and 8—8, of Figs. 3 and 4, respectively, and,

5 Fig. 9 is a partly sectioned elevation, showing a modification of my invention.

In the embodiment of my invention shown in the drawings, I have indicated a door 10 recessed to receive the lock housing, generally indicated

10 at 11. The front wall 12 of the housing 11 is of substantial thickness and is apertured to slidably support the bolt 13 and to provide a stop 14 engageable by the bolt shoulder 15 to limit its outer or locking position into which 15 the bolt is yieldably urged by the spring 16, but which yields to enable the bolt to be retracted into its unlocked position, see Figs. 5 and 6. At 17, I have indicated a strike plate aperture to receive the bolt 13 when in its locking position 20 and the door 10 is closed. The outer side wall 18 of the housing 11 has a pair of spaced parallel guides 19 to assist in the proper support of the bolt 13.

I provide the bolt 13 with a slot 20 extending 25 forwardly a substantial distance from its rear end and communicating with a vertical cylindrical bore 21, the diameter of which is greater than the width of the slot 20. The bore 21, when the bolt is in its locked position, receives 30 the bolt anchor 22 which is preferably in the form of a rod slidably mounted in the housing wall 12 and yieldably urged towards its bolt anchoring or first position by means of a spring 23.

My bolt 13 includes a lever 24 pivotally supported as at 25 in the slot 20 and which has, 35 adjacent its rear end, a shoulder 26. Below the rear end of the lever 24, the bolt slot 20 is bridged as at 27 to provide a shoulder against which the spring 16 works and which establishes 40 a seat for the spring 28 yieldably urging the rear end of the lever 24 upwardly against the stop 29 as shown in Fig. 5. The lever 24 is of sufficient length so that its front portion extends forwardly into the bore 21 and preferably 45 it is so formed that its front and rear portions are disposed at an angle to each other so that in its position shown in Fig. 5, the front portion extends downwardly and forwardly under the bolt anchor 22 and its rear portion is substantially flush with the upper edge of the bolt 13 while in its Fig. 6 position, said front portion is flush with said upper bolt edge.

From the foregoing and from a consideration of Figs. 5 and 6, it will be appreciated that the bolt 55 13, in its locking position, is positively retained

by the bolt anchor 22 and can not be retracted unless and until the bolt anchor 22 is raised into its inoperative or second position. In accordance with my invention, I provide for the retraction of the bolt 13 to make my lock adaptable to a wide range of security requirements.

These may first be considered as providing for the unlocking of the door from the outside as by the use of a key and from the inside as by turning a handle. To accomplish this basis of lock operation, I secure to the outer housing side wall 18 any conventional key operated lock unit 30 having a key rotated cylinder cam 31 disposed above but adjacent the lever shoulder 26.

At 32, I have indicated an inside wall or support which is anchored by screws to the inset front wall projection 33 and to the studs 34, 35, and 36, with the stud 34 also serving as an anchor for the spring 46. Coaxial with the cylinder cam 31 is a hollow sleeve 37 extending through the support wall 32 with its head flange 38 disposed adjacent the cylinder cam 31. The sleeve 37 receives a spindle 39 within it while a ring 40 fits over it. The parts 37, 39 and 40 are interconnected thereto by a pin 41 locked in place by a ring 42. The spindle 39 is rotated, when the handle 43 is released, by a coiled return spring 44 anchored to the stud 35. I secure a cover 45 to the front wall 12, the door 10 and to the studs 34, 35 and 36 and through it extends the spindle 39 to receive the handle 43.

In order that the door 10 may be unlocked by turning the key of the unit 30 or the handle 43, I provide the head flange 38 with an arm 46 having a shoulder 47 and an offset catch 48. The shoulder 47 is disposed to be engaged by the cylinder cam 31 so that the catch is swung between its Fig. 5 and 6 positions when either said cam or the handle 43 is turned. It will be appreciated from a consideration of Figs. 5 and 6 that as the catch 48 swings, it first depresses the lever 24 thereby moving the bolt anchor 22 into its inoperative position and then engages the lever shoulder 26 to draw the bolt 13 into its unlocked position.

The usual requirements are for a door to have a handle on the outside and such is indicated at 49 having its spindle 50 extending through the side wall 18 and the support wall 32 where it is anchored to the ring 51 by the pin 52. The ring 51 includes an arm 53 connected to the screw for the stud 34 by the return spring 54 and an arm 55. The pin is held in place by a cap 56.

In order that the bolt 13 may be retracted by turning the outside handle 49, I mount on its spindle 50 a link 57 that is free to turn independently thereof and having a stud 58 disposed to extend through the arcuate slot 59 in the support wall 32 for engagement by the arm 55. Pivots connected to the bolt 13 and to the link 57 is a second link 60. In the locking position of the bolt 13, the links 57 and 60 are partially jackednifed but when the bolt is retracted, said links are so straightened as to constitute a single link connection between the spindle 49 and the bolt 13. The stud 36 prevents the links from swinging too far beyond center and the links are also under the influence of the spring 61.

The linkage just described is, of course, moved whenever the bolt 13 is retracted by turning the key or the inside handle 43 and also is operative to enable the bolt 13 to be retracted by the outside handle 49 when the bolt anchor 22 is inoperatively positioned. Such linkage is preferred when means for holding the bolt 13 in its unlocked position are

desired but such linkage requires the use of means to release the bolt 13 when the door 10 is closed.

As a preferred embodiment of such bolt release means, I have shown front wall projection 33 as formed with a passageway slidably supporting a latch 62 adapted to be engaged and forced inwardly by the strike plate 17. The latch 62 has a stem 63 extending freely through the seat 64 between which and the latch 62 is located the latch return spring 65. Mounted on the stem 63 and confined between stops 66 and 67 for limited sliding movement relative to the stem 63 is a carrier 68 influenced by a spring 69 seated between it and the stop 66. I provide the carrier 68 with a pivotable trip 70 yieldably backed by the spring 71. I provide the link 57 with a shoulder 72 which, when the bolt 13 is held in its retracted position, is disposed to be engaged and rotated by the trip 70, thereby to rotate the linkage sufficiently to enable it to jackknife when the latch 62 is depressed, so that the spring 46 becomes operative to seat the bolt 13.

For many uses, it is desirable to have electrically operated means to release the bolt anchor 22 from within the area protected by the lock and my use of a bolt anchor 22 within the lock housing 12 is well adapted to be thus operated. For that purpose, I mount in the housing 11, an electromagnet unit 73 fast on the stem 74 of which is a collar 75 receiving one end of a bell crank lever 76 pivotally mounted on the housing front wall 12. The other end of the bell crank lever 76 engages a recess 77 in the bolt anchor 22. The circuit to the electro-magnet unit 73 is indicated at 78 and its switch (not shown) may be located where desired.

If desired, the bolt 13 may be provided with a second recess 79, in Fig. 9, located to receive the bolt anchor 22 when the bolt 13 is retracted into its unlocked position thereby to provide means for automatically holding the bolt 13 unlocked until the electromagnet unit 73 is again energized. I have also shown the bolt 13 as having a bore to receive the hardened steel end 80.

From the foregoing, it will be appreciated that locks in accordance with my invention are well adapted to meet a wide range of security conditions for the door equipped therewith can be readily opened from the inside by means of the inside door handle and can also be opened from the outside as by means of a key. It can not, however, be opened by means of the outside handle unless the bolt anchor is retracted as by use of the key, turning the inside handle, or by remote control as by energizing the electromagnet unit. At the same time, the bolts of my locks may be automatically held open when retracted by any of the bases of control.

What I therefore claim and desire to secure by Letters Patent is:

1. A door lock comprising a support, a bolt carried by said support for movement between an exposed locking position and a retracted unlocked position, a bolt anchor carried by said support to slide at right angles to the bolt axis between operative and inoperative positions, said bolt including a shoulder engageable by said anchor when said bolt is in its locking position and said anchor is in its operative position, a member pivotally carried by said bolt for movement between a first position and a second position and engageable with said anchor, and a bolt retracting unit to actuate said member from its first to its second position to move said anchor into its inoperative position and said

member in its second position operatively connecting said bolt to said unit.

2. A door lock comprising a support, a bolt carried by said support for movement between an exposed locking position and a retracted unlocked position, a bolt anchor carried by said support to slide at right angles to the bolt axis between operative and inoperative positions, said bolt including a shoulder engageable by said anchor when said bolt is in its locking position and said anchor is in its operative position, a member pivotally carried by said bolt for movement between a first position and a second position and engageable with said anchor, a key operated unit, a handle unit, said units being located on opposite sides of said support, and means connecting said units to said member and operable on the actuation of either unit to actuate said member from its first to its second position to move said anchor into its inoperative position and said member in its second position operatively connecting said bolt to said unit.

3. A door lock comprising a support, a bolt carried by said support for movement between an exposed locking position and a retracted unlocked position, a bolt anchor carried by said support to slide at right angles to the bolt axis between operative and inoperative positions, said bolt including a shoulder engageable by said anchor when said bolt is in its locking position and said anchor is in its operative position, a member pivotally carried by said bolt for movement between a first position and a second position and engageable with said anchor, a bolt retracting unit to actuate said member from its first to its second position to move said anchor into its inoperative position and said member in its second position operatively connecting said bolt to said unit, and electrically operated means carried by said support to move said anchor into its inoperative position independently of said member.

4. The door latch of claim 3 in which the bolt has a second shoulder disposed to receive the anchor when the bolt is in its retracted position.

5. A door lock to be mounted in a door in desired relation to a strike plate, said lock comprising a support, a bolt carried by said support for movement between an exposed locking position and a retracted unlocked position, a bolt anchor carried by said support to slide at right angles to the bolt axis between operative and inoperative positions, said bolt including a shoulder engageable by said anchor when said bolt is in its locking position and said anchor is in its operative position, a member pivotally carried by said bolt for movement between a first position and a second position and engageable with said anchor, a bolt retracting unit to actuate said member from its first to its second position to move said anchor into its

inoperative position and said member in its second position operatively connecting said bolt to said unit, and means operable to hold said bolt in its retracted position and comprising first and second links, a pivot interconnecting said links, pivotal connections between said first link and said bolt and said second link and said support, and a stop carried by said support, said links being jack-knifed in the locking position of said bolt and in the retracted position thereof being so straightened that said pivot is located on the opposite side of said center line between said pivotal connections and said second link is in engagement with said stop, a latch carried by said support for engagement with said strike plate and operable by such engagement, and a connection between said latch and said second link to initiate the jack-knifing of said link.

6. The door latch of claim 5 and a handle, said handle being co-axial with the pivotal connection between the second link and the support, and a connection between said handle and said second link to operate only in a bolt retracting direction.

7. A door lock comprising a support, a bolt carried by said support for movement between an exposed locking position and a retracted unlocked position, a bolt anchor carried by said support to slide at right angles to the bolt axis between operative and inoperative positions, said bolt including a shoulder engageable by said anchor when said bolt is in its locking position and said anchor is in its operative position, a member provided at its rear end with a shoulder and pivotally carried by said bolt for movement between a first position and a second position and engageable with said anchor, a key operated unit including a cylinder cam located on one side of said support, and an inside handle unit co-axial with said key unit and located on the other side of said support, a member carried by said handle unit including a shoulder engaging arm and a shoulder engageable by said cylinder cam whereby operation of either unit is effective to actuate said member to move said anchor into its inoperative position and said member in its second position operatively connecting said bolt to said unit.
